[57] CLAIM

The ornamental design for anchor rope guard, as shown and described.

DESCRIPTION

FIG. 1 is a rear elevational view of an anchor rope guard showing my new design;
FIG. 2 is a side elevational view thereof;
FIG. 3 is a front elevational view thereof;
FIG. 4 is a side elevational view opposite to FIG. 2;
FIG. 5 is a top plan view thereof;
FIG. 6 is a bottom plan view thereof; and
FIG. 7 is a left side, top and front isometric view of a second embodiment thereof, the sole difference from the first embodiment being the vertically dependent hook-like panel shown in FIG. 7, and it is understood to be otherwise similar, in all views, to the first embodiment except for that difference.
